UNITED STATES PATENT OFFICE.

MORTIMER C. ROSENFELD, OF CLEVELAND, OHIO.

CONTAINER.

1,158,558.

Specification of Letters Patent.

Patented Nov. 2, 1915.

Application filed January 22, 1914. Serial No. 813,650.

To all whom it may concern:

Be it known that I, MORTIMER C. ROSENFELD, a citizen of the United States, residing at Cleveland, in the county of Cuyahoga and State of Ohio, have invented a certain new and useful Improvement in Containers, of which the following is a full, clear, and exact description, reference being had to the accompanying drawings.

10 This invention relates to containers or cartons such as are used for inclosing articles of hardware, pipe fittings, and the like; and it has for its principal object to provide a container or carton in which articles of the 15 aforesaid character may be securely packed for shipment, and which may thereafter be placed upon the store shelves for containing the articles in stock and from which the dealer may conveniently remove the articles 20 as occasion requires.

It will be understood that, heretofore, it has been the practice to ship small articles of hardware, pipe fittings, etc., in packages or boxes from which they are transferred, 25 by the dealer, to permanent bins which form a part of his store equipment. These bins are provided with front walls which have semi-circular openings that extend from the top of the bin to within a short distance of 30 its bottom, that portion of the front wall below the opening acting to retain the articles within the bin.

In carrying out the aforesaid object, I provide one of the end walls of my container with an opening, similar to the opening in the front wall of the usual bin so that the container, when placed upon the shelf, is in effect a bin, and in this manner, my invention obviates the unpleasant and time 40 consuming task of having to transfer the goods from packages to bins.

Further, and more limited objects of my invention are to provide a container of the above class which is preferably formed from 45 a single blank of heavy card board and which, because of its peculiar construction is extremely strong; which, when partially assembled, is collapsible; and which, from its collapsed condition, can be quickly and 50 easily built up for use. (The collapsible feature enables a great number of containers to be stored in a comparatively small space and this is a very important item with concerns using this class of containers).

One embodiment of my invention whereby 55 the above objects are attained, is illustrated in the accompanying drawings forming a part hereof, wherein Figure 1 is a perspective of my improved container, the same being assembled and in condition for use; 60 Fig. 2 is a similar view, showing the manner of building up the container; Fig. 3 is a central, vertical, longitudinal section through the container, the same being taken on the line 3-3 of Fig. 4; Fig. 4 is a horizontal 65 section which corresponds to line 4-4 of Fig. 3; Fig. 5 is a transverse section on the line 5-5 of Fig. 4; Fig. 6 is a plan view of the blank from which the container is formed; and Fig. 7 is a perspective view 70 which shows a number of my containers in place on shelves, as they would appear in use, one of the containers being shown open.

For convenience of description, I will refer to that end of the container which is 75 displayed, when the container is placed upon the shelves, as the front thereof, the terms which I apply to the top and other walls of the container being determined also by the position which it occupies upon the shelves. 80

The dotted lines in Fig. 6 indicate where the blank is bent or folded in the formation of the container; and the substantially square sections 1 and 2 (which are inclosed by certain of the dotted lines) represent the 85 bottom and top of the container, respectively. In the building up of the container from the blank, the blank is bent or folded upon the dotted line *a* until the side wall 3 is at substantially right angles to the bottom 1. The top wall 2 is then folded over 90 on the line *b* until it is substantially parallel with the bottom, when the side wall 4 may be bent downwardly along the line *c* until it is parallel with the wall 3. The free edge 95 of the wall 4 is then secured to the flap 5 (preferably by staples 6) which flap is bent up from the left hand edge of the bottom 1 on the line *d*. The appearance of the container, at this stage of development, is illustrated in Fig. 2. The next step is to turn inwardly the flaps 7 and 8, which extend from the rear ends of the walls 3 and 4, respectively, the ends of said flaps overlapping. The flap 9, which extends rearwardly 100 from the bottom 1, is then bent up over the flaps 7 and 8, and the flap 10, which extends rearwardly from the top wall 2, is bent 105

downwardly over the flap 9. In these positions the parts are securely fastened together (preferably by gluing).

As I have stated hereinbefore, it is required that the front wall of the container be provided with an opening (preferably semi-circular in shape) which extends from the top of the container to within a short distance of its bottom. The front wall of the container is formed by the flaps 11 and 12, which extend from the forward edges of the side walls 3 and 4, respectively, and each of these flaps has its upper, free corner cut away to produce a notch which is of such a design that, when the flaps are turned inwardly until they are in a common plane, they produce a wall having an opening of the desired shape. To firmly hold these flaps in position, I secure (preferably by glue) the lower portion of the cover 13, which extends from the forward end of the bottom 1, to the front wall below the aforesaid opening. Above the portion which is thus secured to the front wall of the container, the cover 13 is free to swing upon a line whereon the cover is creased, such line being represented by the dotted line *e* in Fig. 6. The cover 13 is also creased upon the line *f*, near its upper edge, to produce a flap 14 which may be inserted beneath the top of the container and above the upper edges of the flaps 11 and 12, where it may be temporarily fastened by glue or other means.

From the foregoing description it will be seen that my invention provides a very simple and comparatively cheap container for articles of the character previously specified; which, notwithstanding the fact that it may be made of heavy card-board, is very strong so that it will withstand the treatment to which such containers are subjected in shipment; which may be very conveniently used upon the dealer's shelves for containing the articles in stock and from which the articles may be very easily removed; and the cover, whereby the front end of the container may be closed, protects the contents from dust and other deteriorating elements, and answers also as a means of supporting a label.

It will be apparent from an inspection of Fig. 2 that, before the end flaps have been folded into final position, it is an easy matter to collapse the container by pressing the top and the bottom together until the sides 3 and 4 are parallel thereto. In the collapsed condition of the container, the top and bottom are offset one from the other, of course, a distance corresponding to the height of the walls 3 and 4.

Having thus described my invention, what I claim is:—

1. A container of the character set forth having a substantially vertical wall which is provided with an opening that extends

from its upper edge toward its lower edge, a reinforcing strip secured to said wall below the opening whereby the wall is strengthened, and a closure for said opening which is hingedly connected to said strip. 70

2. A container of the character set forth having a front wall which is composed of two members each having a vertical edge that is connected to the forward edge of one of the sides of the container and a horizontal edge that extends parallel and adjacent to the front end of the bottom of the container, each of the members having its upper, free corner cut away to produce a notch, the notches in both members coöperating to form an opening, and a flexible closure for said opening which has a portion secured to the aforesaid members below the opening. 75 80

3. A container of the character set forth having a front wall which is composed of two members each having a vertical edge that is connected to the forward edge of one of the sides of the container and a horizontal edge that extends parallel and adjacent to the front end of the bottom of the container, each of the members having its upper free corner cut away to produce a notch, the notches in both members coöperating to form an opening, a strip which has connection with the front end of the bottom and extends upwardly over and is secured to the lower portion of the aforesaid members, and a closure for the aforesaid opening which has its lower edge hingedly connected to the strip. 90 95

4. A container of the character set forth comprising top, bottom, side and rear walls, extensions on the forward ends of the side walls which have horizontal edges that align with the front end of the bottom wall when the extensions are turned inwardly and which have their upper, free corners cut away to produce notches that coöperate to form an opening that extends from the top wall toward the bottom wall and decreases in width from top to bottom, and an extension from the front end of the bottom wall which has a portion that is secured to the front surfaces of said extensions below the aforesaid opening and another portion which is hingedly connected to the first mentioned portion and is arranged to close the opening. 110 115

5. A container of the character set forth which is formed from a single blank of flexible material and comprising top, bottom, and side walls, extensions which project from the rear ends of the aforesaid walls and which coöperate when folded inwardly, to produce a rear wall for the container, an extension which projects from the forward end of each of the side walls and arranged to be turned inwardly until they are in a common plane, the upper, free corner of each extension being cut away to produce a notch, the notches in the two extensions co- 120 125 130

operating to form an opening, and an extension on the forward end of the bottom wall of the container which has a portion that is secured to the front surfaces of the last mentioned extensions below the aforesaid opening and having another portion which is adapted to close said opening, said extension having a flap along its free edge that is arranged to project between the upper edges of the aforesaid extensions and the adjacent edge of the top wall when the extension is over said opening.

5 In testimony whereof, I hereunto affix my signature in the presence of two witnesses.

MORTIMER C. ROSENFELD.
